[57] CLAIM

The ornamental design for a tennis bracelet pendant, as shown and described.

DESCRIPTION

FIG. 1 is a end elevational view of the clasp end of the tennis bracelet pendant showing my new design;

FIG. 2 is a bottom view of the tennis bracelet of FIG. 1;

FIG. 3 is an end elevational view of the link end of the tennis bracelet of FIG. 1;

FIG. 4 is a top view of the tennis bracelet, with a segment (shown in phantom lines) of the chain attached, of FIG. 1; and,

FIG. 5 is a side elevational view of the bracelet of FIG. 1. The broken line showing of a chain, in FIG. 4, is for illustrative purposes only and forms no part of the claimed design.
